I. A. WEAVER

AUTOMOBILE RADIATOR FLOW INDICATOR

Filed May 20, 1926

Inventor:
See A. Mann.
By Walter M. Fuller, Atty.

UNITED STATES PATENT OFFICE.

IRA A. WEAVER, OF SPRINGFIELD, ILLINOIS.

AUTOMOBILE RADIATOR FLOW INDICATOR.

Application filed May 20, 1926. Serial No. 110,525.

My invention relates to automobile radiator flow meters or indicators to show to the chauffeur of the vehicle the manner in which the water-cooling system of his car is functioning.

One aim of the invention is the provision of an appliance of this type which will disclose or reveal the manner in which the cooling water is entering the radiator, and also the condition of such water, as well as its height or level in the radiator.

If the water is flowing properly into and from the radiator, that fact will be apparent from the way in which the device operates.

On the other hand, if the water-circulation system is stopped up or partially clogged, a change in the functioning of the indicator will be shown.

Also, if the water reaches such a temperature that it boils, this condition of affairs will become obvious from the mode of working of the appliance.

The new device is intended to take the place of or act as a substitute for the well known motometer, and to perform in addition to its purely temperature-indicating action, the other specified desirable operations.

A further purpose of the invention is the production of an apparatus of this character and having the capabilities referred to, which is simple in construction, which is reliable and effective in its operation, and which can be produced at a relatively small cost.

To enable those acquainted with this art to fully understand the structural and functional advantages accruing from the employment of this invention, in the accompanying drawing, forming a part of this specification, and to which reference should be had in connection with the following detailed description, two desirable or preferred embodiments of the invention have been shown more or less in detail, the same reference characters being used throughout the several views for like parts.

In this drawing,—

Fig. 1 is an elevation of the new and improved device, showing it as applied to a radiator-neck cap and illustrating a small section of the radiator itself;

Fig. 2 is a central, vertical, longitudinal section through the entire appliance;

Fig. 3 is a horizontal section on line 3—3 of Fig. 2;

Fig. 4 shows the novel indicator applied to the top of a radiator in a somewhat different

manner, the radiator and its cap being illustrated in section; and

Fig. 5 is an enlarged horizontal section through the tapering sleeve surrounding the small turbine at the point where the admission pipe or tube is pivotally or hingedly connected thereto.

The new and improved water-flow indicator or meter is constructed and intended to be carried or fixed on the automobile radiator-cap 11, which is ordinarily detachably or otherwise mounted by means of co-operating screw-threads on the threaded neck or filling-spout 12 of a radiator 13.

Such cap is centrally apertured at 14 for the extension therethrough of a sheet-metal, tubular member 15 having an outer or upper part 16 of enlarged diameter, its lower, smaller section extending down through the cap-hole and being fitted inside of the cap with a threaded nut 17 and a gasket or washer 18 between the end of the nut and the under face of the cap, thereby forming a vapor and water tight connection between the parts.

Hence the nut securely and firmly holds the hollow or tubular member 15 fixedly in position on the cap.

Screwed into the lower end of the member 15, I employ an open-ended, depending, longitudinally-slotted, tubular casing 19, the walls of which between the slots or elongated apertures are deflected or curved inwardly somewhat, as shown in Fig. 3, in order to direct any liquid flowing inwardly through such passages toward the center.

The element 19 constitutes an outer, stationary casing or apertured shell of a small water turbine, the companion or correlated propeller or rotary member of which is a twisted or spiral bar 21, the lower end of which has a bearing 22 receiving a supporting, stationary pin or shaft 23, the upper end of the twisted bar having an extension 24 carrying one or more horizontal, permanent magnets 25 at its top end, a guide 26 surrounding the part 24, which assures its substantial upright position at all times.

Surmounting the member 15 is a glass or other transparent cylinder 27, closed or covered at its top end by a metal cap 28 of pleasing design, the lower end of such container being fastened to the externally screw-threaded part 16 by a suitably shaped ring 29, in which the lower section of the glass body fits.

A flat, metal disk 31 is interposed between the members 27 and 29, all as is clearly shown in Fig. 2.

The parts closing the opposite ends of the 5 transparent shell or casing are seated or otherwise secured thereto in an air-tight manner, and the interior of the glass cylinder is under substantial vacuum by reason of its air being drawn off or abstracted in the 10 usual way by an appropriate air pump.

This sub-atmospheric pressure in the glass compartment not only facilitates the rotation of the indicator therein, described herein-after, but the outer air pressure tends to 15 hold the parts firmly together.

Secured to the center of the round disc or plate 31, I provide an upright standard or post 32, the top end of which has a vertical bearing 33 for a pin or shaft 34 fastened to 20 the center of and depending centrally within an inverted, rotary, cup-shaped indicator, supplied externally with a series of multi-colored, spiral bands or stripes 36, by means of which the relative speed and comparative 25 uniformity of rotation of the member 35 may be easily determined or judged by merely looking at them.

The lower end of the indicator 35 carries one or more transverse or horizontal, permanent magnets 37, by means of which the indicator is rotated through the revolution of 30 the complementary, rotary, driving magnet or magnets 35.

In order to cover the magnet or magnets 35 37 so that they cannot be seen through the enclosing glass casing, a shield 38 of appropriate form is used in the relation indicated for that purpose.

Thus the rotation of the propeller or rotor 40 of the small turbine is transmitted through the two sets of co-operating magnets to the indicator in a sealed vacuum container, and, accordingly, there is no possibility of water, moisture, vapor or dirt entering the closed 45 compartment, and there is no danger of any of these escaping through or around the cap.

It will be understood that there is no direct 50 mechanical connection between the driving means and the indicator and its operator.

Such a construction avoids the use of a 55 shaft extending through the cap, which would probably necessitate the employment of some form of stuffing box therewith, which, obviously, would have certain objectionable characteristics.

The turbine of this construction projects 60 downwardly into the top part or head portion of the interior of the radiator, where it is subject to the action of the water entering the radiator at that point, either by reason of the operation of a pump or through thermo-siphonic action.

When an adequate quantity of water is in 65 the radiator, a part of the entering water, or that already in the radiator, flows into the

turbine through the upright longitudinal slots or openings of the casing or shell 19, and, by reason of such entrance and descent and discharge through the open, lower end of such shell, the rotary member or propeller 70 21 is caused to revolve at a speed substantially proportional to the speed of operation of the engine of the automobile.

The rotation of the magnetic means 25, by 75 reason of its electrical attraction for the complementary magnetic means 37 in the sealed vacuum chamber, produces the revolution of such upper magnetic means and its associated indicator 35, which is clearly visible to the driver of the automobile through the transparent glass shield.

A substantially uniform rotation of the indicator at a proper speed informs the chauffeur that the cooling system of his engine is 80 functioning properly.

If the driving connection for the pump of the cooling system breaks, or if the radiator or its connections become clogged with sediment, or if the hose connections therefor become closed, as they sometimes do by reason of disintegration of the material forming such connections, no water will be delivered to the turbine, and the non-rotation of the indicator will disclose to the observer that the 85 cooling system needs immediate attention to 90 remedy the trouble.

If the indicator turns at too slow a speed, 95 it will be apparent that the water-cooling system is not operating at full efficiency and inspection and correction of the difficulty is 100 needed.

If the water level in the radiator becomes 105 low, and the water begins to reach the boiling point, it will enter the turbine irregularly or in gushes, causing the indicator to revolve 110 erratically, or not smoothly and evenly, thus giving a warning of danger, so that replenishing water may be added to the radiator before harm results.

The spiral or helical stripes or bands on 115 the indicator give material aid in showing the manner in which this member is turning.

In Figs. 4 and 5 of the drawing a somewhat modified construction is shown, wherein in a tapered sleeve 41 hangs suspended from the top of the radiator-neck, and encases the 120 turbine structure, being held in position by the screw-threaded radiator-cap member 11.

Such sleeve has an entrance tube or pipe 41 hinged thereto at 43 and extending into the entrance pipe 44 of the radiator 45, the hinge construction being provided to facilitate the insertion of the appliance through the radiator-neck, but, of course, it will be understood that the tube may be made flexible, if 125 preferred.

A portion of the water traveling up 130 through the pipe 44 flows through this bypass tube 42 and enters the casing 41 at one side thereof, as indicated in Fig. 5, above the

level of the water in the top compartment of the radiator, as shown in Fig. 4.

Such a construction provides a more positive movement of the rotor or propeller of the turbine within the sleeve, which is of the same construction as or equivalent to the structure already presented.

Although I have shown the by-pass tube as receiving its liquid from the supply in the entrance pipe of the radiator, it is to be understood that, if preferred, it may receive its water from some other portion of the cooling system.

Although I have in this application presented only two embodiments of the invention, it will be recognized by those skilled in this art that it is susceptible of a variety of other embodiments varying from those shown and described in various ways, and consequently the invention is not limited to the precise and exact structural details shown, the scope of the invention being defined by the appended claims.

I claim:

1. A cap for automobile radiator necks having, in combination, a turbine adapted to be positioned in the radiator when the cap is on the radiator neck and to be rotated by the movement of a cooling liquid therein, magnetic means rotated by said turbine, a transparent casing on said cap having a partial vacuum therein, a visible spirally-striped rotary indicator in said casing, and magnetic driving means for said indicator in said casing, whereby the rotation of said turbine revolves said indicator through said two magnetic means.

2. A cap for automobile radiator necks having, in combination, a rotary turbine adapted to be positioned in the radiator when the cap is on the radiator neck and to be rotated by the movement of a cooling liquid therein, said turbine comprising a slotted open-ended casing and a spiral propeller mounted therein, a visible indicator, and means operatively connecting said propeller and said indicator, whereby rotation of said turbine effects the revolution of said indicator.

3. A cap for automobile radiator necks having, in combination, a rotary turbine adapted to be positioned in the radiator when the cap is on the radiator neck and to be rotated by the movement of a cooling liquid therein, said turbine comprising a slotted open-ended casing and a spiral rotary propeller therein, a sleeve surrounding said casing, an entrance pipe for said sleeve for the delivery of liquid thereto for the operation of the turbine, a visible indicator, and means operatively connecting said propeller and indicator, whereby rotation of the turbine effects the revolution of said indicator.

4. A cap for automobile radiator necks

having in combination, a cap-body adapted to be mounted on the radiator-neck, a turbine depending therefrom and designed to be positioned to be actuated by the water flowing through the radiator, said turbine comprising an open-ended longitudinally-slotted casing and a spiral rotary propeller therein, magnetic means rotated by such propeller, a closed transparent casing on the top of the cap and having a partial vacuum therein, a second magnetic means in said casing rotated by said first magnetic means, a spirally-striped indicator in said casing revolved by said second magnetic means, and a shield in said casing concealing said second magnetic means.

5. A cap for automobile radiator-necks having, in combination, a rotary turbine adapted to be positioned in the radiator when the cap is on the radiator-neck and to be rotated by the movement of the cooling liquid therein, a transparent casing on said cap the contents of which are visible from all sides, a top and bottom closing said casing, magnetic means rotated by said turbine, a visible rotary indicator in said casing, and magnetic means associated with said indicator, whereby the rotation of said turbine revolves said indicator through said two magnetic means.

6. A cap for automobile radiator-necks having, in combination, a rotary turbine adapted to be positioned in the radiator when the cap is on the radiator-neck and to be rotated by the movement of the cooling liquid therein, a transparent casing on said cap the contents of which are visible from all sides, a top and bottom closing said casing, the latter having a partial vacuum therein, magnetic means rotated by said turbine, a visible rotary indicator in said casing, and magnetic means associated with said indicator, whereby the rotation of said turbine revolves said indicator through said two magnetic means.

7. A cap for automobile radiator-necks having, in combination, a rotary turbine depending from the cap and adapted to be positioned in the radiator when the cap is on the radiator-neck and to be rotated by the movement of the cooling liquid therein, a sleeve adapted to fit in the radiator-neck and to extend down into the radiator surrounding said turbine, a pipe connected to said sleeve and adapted to extend into the conduit connecting the radiator to the engine of the automobile and to deliver liquid into said sleeve for the operation of said turbine, a visible indicator, and means operatively connecting said turbine and indicator whereby the former revolves the latter.

In witness whereof I have hereunto set my hand.

IRA A. WEAVER.
